GARMENT MARKER

Abraham Robert Price, San Francisco, Calif.

Application September 2, 1936, Serial No. 99,115

5 Claims. (Cl. 33—9)

My invention relates to improvements in garment markers and it consists of the combinations, constructions and arrangements hereinafter described and claimed.

5 An object of my invention is to provide a garment marker which is an improvement over the form of the device shown in my Patent No. 1,404,318, issued January 24, 1922. In the patented device I show a hollow ring for encircling the skirt, and this ring is adjustable to the desired height above the floor or other supporting surface. The ring is provided with a plurality of small openings on its inner side and novel means is used for forcing talcum powder or other powdered marking material into the ring and through the openings for marking the skirt or other garment. The skirt is worn by a person during the marking, and in this way an accurate and rapid marking of the skirt is made possible.

10 In the present invention I provide a split hollow ring for encircling the skirt, and a portion of this ring may be swung away from the other portion to permit the person to enter the ring without the necessity of stepping over the ring.

15 After the person has entered, the movable portion of the ring may be swung back into position. I provide an improved means for conveying the powdered marking material such as talcum powder or the like to the hollow ring and the ring in turn has small openings on its inner side that will direct the material against the garment.

The ring is mounted on a sleeve that is adjustably secured to a standard and this standard is marked to indicate the height of the ring above the supporting surface. The sleeve may be adjusted on the standard and secured in adjusted position. The pump for forcing air into the container carrying the powder or other marking material is preferably secured to the top of the sleeve and in a position where it may be readily actuated.

45 Novel means is provided for inclining the ring at a slight angle to the horizontal if it is desired to mark the skirt in such a manner. The ring also may be swung into inoperative position, and this movement will cut off communication between the container for the marking material and the ring.

50 Other objects and advantages will appear in the following specification, and the novel features of the device will be particularly pointed out in the appended claims.

55 My invention is illustrated in the accompany-

ing drawings forming a part of this application, in which—

Figure 1 is a side elevation of the device;

Figure 2 is a section along the line 2—2 of Figure 1;

Figure 3 is a section through a portion of the hollow ring;

Figure 4 is a section along the line 4—4 of Figure 3;

Figure 5 is a section similar to Figure 4 but showing the parts in a different position;

Figure 6 is an end view showing the swingable portion of the hollow ring in open position;

Figure 7 is a section along the line 7—7 of Figure 1;

Figure 8 is a section along the line 8—8 of Figure 2;

Figure 9 is a section along the line 9—9 of Figure 2; and

Figure 10 is a side elevation of the pump and associate mechanism.

In carrying out my invention I provide a standard comprising a base 1 and an upright 2. The upright is square in cross section and has markings 3 on one face thereof, as shown in Figure 10. These markings indicate inches and half inches and their purpose will be described hereinafter.

A sleeve indicated generally at 4 is adjustably mounted on the upright 2 and may be locked in adjusted position by means of a wing nut 5 that is carried at the top of the sleeve and is designed to enter any one of several depressions 6 formed in the side of the upright containing the markings 3, see Figure 10. I have shown the depression 6 disposed every inch apart, although additional depressions may be provided if desired. The sleeve 4 may be moved with respect to the upright 2, and then the set screw 5 adjusted for securing the sleeve in position.

Near the bottom of the sleeve I provide a cross arm 7 and one end of this arm is designed to removably receive a cap 8. Figure 9 shows the cap 8 secured to the arm 7 by means of a set screw 9 or other suitable fastening means. The arm 7 is hollow, and the free end that receives the cap 8 is plugged by a block 10.

A tube 11 extends through a portion of the plug 10 and then is bent in the manner shown in Figure 2 so as to extend through an opening 50 in the wall of the hollow arm 7. The sleeve portion of the cap 8 is provided with a slot 12 for receiving the tube 11 that projects from the wall of the arm 7.

In Figure 2 I also show the tube 11 extending 55

diametrically across a container 13. The tube extends through both sides of the container and has its free end telescoping into a conduit 14. The conduit 14 has an inner wall that enters the interior of the tube 11 as well as an outer wall that encloses the same tube. In this way a tight seal is made between the conduit and the tube.

Figure 1 shows the conduit 14 leading from the tube 11 to a pump 15. Figure 10 shows the conduit 14 provided with a check valve 16. The stem 17 of the check valve is provided with a shoulder 18 that bears against a supporting member 19 that in turn is carried by a collar 20. The collar is rigidly secured to the sleeve 4 and has a ring 21 secured thereto. The pump 15 sits within the ring 21 and rests upon the supporting member 19. The stem 17 has its upper end screwed into the bottom 22 of the pump casing, and in this way the pump is locked against the support 19 and is held against vertical movement by the shoulder 18 bearing against the support 19.

The tube of the pump casing 15 extends through a second ring 23 and this ring is secured to the sleeve 4 by a second collar 24. A piston 25 reciprocates within the pump 15 and is actuated by a piston rod 26 and a handle 27. During the up-stroke of the handle 27 a ball check 28 in the check valve 16 raises and permits air to enter the pump. A downward movement of the handle 27 will close the ball check 28 and will force the air through the conduit 14 and into the tube 11.

In Figures 2 and 8 I show the tube 11 enclosed by a short sleeve 29 that extends across the inside of the container 13 and projects beyond one side of the container. This sleeve 29 has its end cut to form a half lap joint 30. A stub sleeve 31 is secured to the tube 11 and is provided with a half lap joint 32 cooperating with the joint 30. When the container 13 is slipped onto the tube 11, the sleeve 29 encloses the portion of the tube 11 disposed within the container 13. The sleeve 29 cooperates with the stub sleeve 31 to entirely enclose the portion of the tube 11 projecting from the arm 7. An outer sleeve 31' houses the half lap joint and extends from the cross arm 7 to the container 13. The purpose of the half lap joints 30 and 32 is to align the three small openings 33 in the tube 11 with similar openings 34 in the sleeve 29. A large opening 35 in the tube 11 will also be aligned with an opening 36 of the same diameter in the sleeve 29. A partition 37 extends across the tube 11 and separates the small openings 33 from the large opening 35.

Referring to Figure 8, it will be noted that air entering the tube 11 from the conduit 14 will be forced through the small openings 33 and 34 and down into a quantity of marking material 38 disposed in the bottom of the container 13. The openings 33 and 34 extend in different directions, and cause jets of air to enter the material 38 and to agitate it violently. The air then will flow from the container back into the tube 11 through the aligned openings 35 and 36, and will carry some of the marking material therewith.

In Figure 9 I show the tube 11 projecting beyond the end of the arm 7 and entering a recess 39 formed in the closed end 40 of the cap 8. The closed end 40 is bored transversely for receiving a hollow ring 41. This hollow ring is rotatably mounted in the portion 40 and has a

slot 42 registering with the open end of the tube 11.

The hollow ring 41 is held in the horizontal position shown in Figure 1 by means of members 43 rigidly secured to the ring by set screws 44. The members 43 bear against the sides of the cap 8 and hold the ring against longitudinal movement in the cap while permitting rotative movement. An adjusting member 45 is secured to the members 43, see Figure 9, and carries a set screw 46 that bears against the under side of the cap 8. An adjustment of the set screw 46 will move the member 45 and the member in turn will swing the ring 41 in the closed end 40. In this way the ring may be adjusted into a horizontal position, or it may be moved into an inclined position.

In Figure 1 I show the ring 41 swingable into the broken line position, and a hook 47 is provided for holding the ring in this position. The slot 42 is moved out of registration with the tube 11 when the ring is in the broken line position, and this will cut off communication between the tube 11 and the interior of the ring.

The ring is formed in two sections 48 and 49, and Figure 7 illustrates the closed ends 48' and 49' of these sections. The section 49 carries a clip 50 that is designed to rest upon the section 48 and hold the two ends in alignment. The section 49 has a sleeve 52 that rotates on an extension 53 carried by the section 48. The sleeve 52 has a flange 54 at its free end, and this flange rides beneath a hook 55 carried by the section 48. The flange 54 has a cut away portion 56, see Figure 4, and a projection 57 is provided adjacent to the cut away portion.

When the two sections 48 and 49 of the ring are aligned with each other as shown in Figure 7, the flange 54 is disposed beneath the hook 55 and the cut away portion 56 and projection 57 assume the position shown in Figure 4. When it is desired to open the ring to permit a person to step there-within, the section 49 is swung away from the section 48, and this movement is permitted by the sleeve 52 riding on the extension 53 in a counter-clockwise direction when looking at Figure 4. This will move the projection 57 into contact with the hook 55 and the section 49 will then be held in raised position, as indicated in Figure 6. After the person has entered the ring the section 49 may be swung in a clockwise direction until the clip 50 again rests on the section 48.

It is possible to remove the section 49 from the section 48 and in doing this the clip 50 is sprung over the section 48, and then the sleeve 52 is rotated in a clockwise direction when looking at Figures 4 and 5. This will swing the projection 57 until it contacts with the opposite side of the hook 55. The hook now registers with the recess 56 and the sleeve 52 may be moved longitudinally along the tubular portion 53 for removing the section 59 from the section 48.

The ring 41 is provided with a number of small openings 58 on its inner wall, and Figure 7 shows two openings 59 and 60 provided at the closed ends of the sections 48 and 49.

From the foregoing description of the various parts of the device, the operation thereof may be readily understood.

A cover 61 is removed from the container 13, see Figure 8, and the marking material is placed

within the container whereupon the cover is again secured in place. The ring 41 is swung into operative position as shown by the full lines in Figure 1. The section 41 is swung to permit a person to enter the ring, and then the section is closed. The sleeve 4 is raised to the desired position, and this is indicated by the inch mark disposed adjacent to the top of the sleeve, see Figure 10. The set screw 5 is turned to lock the sleeve in adjusted position. The handle 27 of the pump is now reciprocated once, and this will force air through the container, and this air will pick up the marking material, and will convey it into a hollow ring and out through the small openings 58. The openings 59 and 60 will permit free flow of air through the hollow ring sections so that the marking material will be carried throughout the entire lengths of the sections, and then ejected through the openings 58 and against the skirt or other garment to be marked. The ring section 49 is now raised to permit the person to walk from the ring.

In cases where the skirt does not contact with the ring 41 an auxiliary ring 62, shown in Figure 1, may be used. The ring 62 is split and is provided with legs 63 that will guide the ring 62 downwardly against the ring 41. The ring 62 is slipped underneath the skirt, and then is allowed to descend so that the leg 63 will contact with the ring 41. The ring 62 then will force the skirt against the ring 41 for marking purposes. It is obvious that the ring 62 may be supported by an auxiliary stand not shown, and moved upwardly along the inside of the skirt to move the skirt against the ring 41.

In Figure 2 I show the container 13 attached to the arm 7 by a support 64. The support 64 and the tube 11 will secure the container to the sleeve 4.

While I have shown only the preferred form of my invention, it should be understood that various changes or modifications may be made within the scope of the appended claims without departing from the spirit of the invention.

I claim:

1. In a garment marker, a hollow ring designed to encircle a garment and being provided with a plurality of small openings in its inner wall, a support for the ring, said ring having a swingable section designed to be swung into open position to permit a person to step within the ring, and then to be swung back into closed position, and means for feeding a marking material to the ring for causing this material to issue

from the openings and to mark a garment enclosed by the ring, and means for swinging the ring slightly into an angular position with respect to a horizontal plane and for holding the ring in adjusted position, whereby the bottom of the garment will be marked at an angle to the horizontal. 5

2. In a garment marker, a hollow ring formed in two sections and designed to encircle a garment, one of the sections partially telescoping over the other and being swingable about the axis of the telescoping portion, a stop for limiting the movement of the swinging section when it reaches open position, and a lip carried by the swinging section and resting on the other section when the section is in closed position. 10

3. In a garment marker, a hollow ring formed in two sections and designed to encircle a garment, one of the sections partially telescoping over the other and being swingable about the axis of the telescoping portion, a stop for limiting the movement of the swinging section when it reaches open position, and a lip carried by the swinging section and resting on the other section when the section is in closed position, the free ends of the sections being closed and being provided with an opening adjacent each end, both sections of the ring being provided with small openings on its inner wall, and means for feeding a marking material to the ring for causing this material to issue from the openings. 20 25 30

4. In a garment marker, a standard, a hollow ring pivotally carried thereby, adjustable means for supporting the ring in a horizontal position, a tube for feeding a marking material to the ring, said ring having openings on its inner wall through which the material passes, said ring being swingable into inoperative position when not in use, the communication between the tube and the ring being closed when the ring is in inoperative position. 35 40

5. In a garment marker, a hollow ring having a section swingable into open position to permit a person to enter the ring, the free end of the section being closed and the end of the ring disposed adjacent to the free end also being closed, said ring and section having a plurality of small openings on their inner wall, and means for forcing a marking material into the ring and section for causing it to issue from the small 50 55 openings. 45

ABRAHAM ROBERT PRICE.
